P. H. CASEY

DISPLAY BOX

Filed Oct. 11, 1924

2 Sheets-Sheet 1

UNITED STATES PATENT OFFICE.

PATRICK HENRY CASEY, OF BALTIMORE, MARYLAND.

DISPLAY BOX.

Application filed October 11, 1924. Serial No. 743,094.

To all whom it may concern:

Be it known that I, PATRICK H. CASEY, a citizen of the United States, and a resident of Baltimore, in the State of Maryland, have invented certain new and useful Improvements in Display Boxes, of which the following is a specification.

My present invention relates generally to boxes, and more particularly to foldable pasteboard boxes, my primary object being the provision of a box for the support and display of articles upon counters, tables and the like, and which to this end is provided with means normally forming a part of the box whereby it may be supported in an inclined position upon a display surface and a top flap held open in such display position whereby the contents may be readily viewed.

20 A further object of my invention is the provision of a box of the above nature which may in this way be held in display position so that its contents may be readily viewed, without necessitating the use of other implements or devices beyond those carried by the box and normally forming a part thereof and a still further object is the provision of a box in which the supporting features are completely formed, except as to the mere folding thereof, when the blank of the box is cut in the first instance.

25 In the accompanying drawings which illustrate two forms of my proposed invention,

30 Figure 1 is a perspective view illustrating the practical application of my invention in its display position,

35 Figure 2 is a vertical longitudinal section taken centrally through the box in the position shown in Figure 1,

40 Figure 3 is a top plan view of the blank forming the box of Figures 1 and 2,

45 Figure 4 is a vertical section taken transversely through one side of the box approximately on the line 4—4 of Figure 2,

50 Figure 5 is a perspective view showing a portion of the bottom of the box and illustrating the supporting legs in their effective position,

55 Figure 6 is a perspective view showing a slightly modified construction,

Figure 7 is a central vertical section taken therethrough,

60 Figure 8 is a plan view of the blank of the box shown in Figures 6 and 7, and

Figure 9 is a detail vertical section taken through one side of the box substantially on the line 9—9 of Figure 7.

Referring now to these figures and particularly to Figures 1 to 5 inclusive I have shown a box which it will be noted from the blank illustrated in Figure 3 includes a rectangular bottom section 15 joined at one side by a web 16 forming the rear wall of the box, with a top section 17 having a central flap 18 which may if desired be of the fanciful shape shown or other desired shape. The blank is folded along lines 19 and 20, at opposite sides of the strip 16 forming the rear wall so that the top section 17 may overlie the bottom section 15 in vertically spaced relation.

At its opposite side the top section 17 is connected by a strip 21 with a bottom flap 22, the latter foldable beneath the bottom section 15 along line 23 and 24 at opposite sides of the connecting strip 21 whereby the connecting strip extends around the end flap 25 of the bottom section when the latter is bent upright along its folding line 26 and 27 whereby the bottom flap 22 may extend flatwise against the base of the bottom section 15. The bottom section 15 also has side flaps 28 bendable upright at the sides thereof, each of these flaps being provided adjacent to the inner end of the bottom section with a lengthwise slit 29. At the inner and outer portions of the bottom flap 22 are laterally projecting tongues 30 and 31, which are bendable along and outside of the end portions of the side flaps 28, tongues 30 having notches 32 in their outer edges to form laterally projecting locking tabs 33 adapted to be extended inwardly and upwardly through the slits 29 of the side flaps 28 in the manner shown in Figure 2 so that the bottom flap 22 is thus locked in its position across the lower surface of the bottom section 15. The tongues 30 are formed opposite the connecting strip 21, the latter of which in conjunction with the side flap 25 forms the front wall of the box as seen in Figure 2, while the tongues 31 are formed at the ends of a bendable strip 34 along the outer or free side of the bottom flap 22 which in the folded position extends along the outer side of the strip 16 between the bottom and top sections and forms with the latter the rear wall of the box.

In addition to the foregoing the top sec-

tion 17 has bendable side flaps 34 which in the folded position are extended downwardly over the side flaps 27 and the tongues 29 and 30 of these side flaps, the free ends 35 of flaps 34 being extended inwardly between the bottom section 15 and the sides of the bottom flap 22 as plainly seen in Figure 4.

The cover flap 18 of the top section 17 has adjacent to its connected end a cross slit 36, and the bottom flap 22 has its central area partially cut out along a series of lines to constitute leg forming strips 37 in spaced parallel relation, as well as a cross strip 38 connecting the free ends of said leg forming strips, and a lid supporting strip 39 between the leg forming strips 37. The leg forming strips 37 are bendable along central lines 40 and along end lines 41 and 42 so that they may be doubled upon themselves in the folded position as plainly shown in Figures 2 and 5. Moreover each of the leg forming strips has along its outer side a pair of brace wings 43 which are bent at right angles to the folded legs as in Figures 2 and 5, and which in this position engage at one end the cross strip 38 when the latter is shifted in the bending of the legs until it abuts the inner ends of the legs adjacent to the folding line 41. Near the folding line 41 at the outer sides of the wings 43, the bottom flap 22 has angular slits forming tongues 44 which tongues when lifted to partly overlap the cross strip 38, serve to lock the leg forming strips in the effective position as plainly seen in Figure 5.

When the legs are folded to the effective position shown in Figures 2 and 5, the lid supporting strip 39, which is integral at one end with the cross strip 38, is shifted toward the rear of the box so that its free end may be turned upwardly and its notched extremity 45 projected forwardly through the slit 36 of the cover 18 whereby the box will thus be held in the inclined display position shown in Figure 2 with its cover elevated as in Figure 1 so that the contents of the box are thus plainly exposed to view.

In the modified form of the invention shown in Figures 6 to 9 inclusive, the same construction as described in connection with Figures 1 to 5 inclusive is adhered to for the purpose of holding the box in inclined position and supporting the lid in upwardly inclined open position although the box itself is formed somewhat differently. As seen in the blank, Figure 8, the box body includes a bottom 46 having its central area cut out to constitute the leg forming strips 37^a, cross strips 38^a, top supporting strips 39^a and wings 43^a, connected to the top or lid 47 by a strip 48 and to a bottom lining 49 by strips 50 and 51. When bent upwardly on the folding lines 52 and 53, the strips 48 and 51 constitute the rear and front walls and the strip 50 is then bent inwardly and

downwardly upon the folding line 54 at its inner edge and horizontally upon the folding line 55 at its outer edge so that the bottom lining 49 lays across the inner upper surface of the bottom 46 as plainly seen in Figure 7.

The box bottom 46 also has side extensions 56 and side strips 57, the latter being adapted to be bent at right angles to the front and rear walls 51 and 48 along the folding lines 58 so that their free ends overlap at the box sides. These strips are provided adjacent to their free ends with transverse slits 59 by which the extension strips 57 may be interlocked previous to the inward folding of the side extensions 56 over these interlocked strips as plainly seen in Figure 9, the inner ends of the side strips 56 thus folded being extended beneath the bottom lining 49 at the sides of the latter.

In placing the box in display position as illustrated in Figures 6 and 7, the leg forming parts previously described are shifted and locked in the same manner as before outlined in connection with the form of the invention shown in Figures 1 to 5 inclusive, the notched extremity 45^a of the top holding strip 39^a being extended through a cross 36^a in the top 47.

It is thus obvious both forms of my invention provide for the setting up of the box in display position in a ready simple and effective manner without the necessity of utilizing for this purpose any outside implements or agencies, the desired operation being easily carried through by the means with which the box is equipped and which ordinarily form a part thereof.

I claim:

1. A display box having a lid or cover and having in its bottom portion a central area cut out to form a leg forming strips and a top or cover holding strip, the said leg forming strips being foldable upon themselves to form supporting legs outstanding from the bottom of the box adjacent to its rear portion, and the said top holding strip being shiftable with the leg forming strips whereby to protect rearwardly beyond the box when the leg forming strips are folded, and having means engageable with the cover or top to hold the latter in upright open position.

2. A folded box formed of cardboard and the like having a top or cover and having in its bottom portion an area cut out along parallel lines to constitute spaced leg forming strips and a cover engaging strip, said leg forming strips being bendable upon themselves to form supporting legs extending angularly from the box bottom adjacent to its rear portion, and said cover supporting strip having a notched free end and being shiftable rearwardly with the said leg forming strips when the latter are folded, the

- top or cover having a slit to receive the notched free end of the said cover supporting strip, and cooperating means carried by the box and said leg forming strips to lock the latter in their folded effective position. 5
3. A folded box formed of cardboard and the like having a top or cover and having in its bottom portion an area cut out along parallel lines to constitute spaced leg forming strips and a cover engaging strip, said leg forming strips being bendable upon themselves to form supporting legs extending angularly from the box bottom adjacent to its rear portion, and said cover supporting strip having a notched free end and being 35 shiftable rearwardly with the said leg forming strips when the latter are folded, the top or cover having a slit to receive the notched free end of the said cover supporting strip, said leg forming strips having a cross piece 40 at their free ends and said box having angular tongues at opposite sides of the leg forming strips with which the cross strip is engageable to lock the leg forming strips in their folded effective positions, and brace 45 wings along one side of each of the said leg forming strips for bracing the latter in their folded effective positions.
4. A folded box formed of cardboard and the like having a top or cover and having in its bottom portion an area cut out along parallel lines to constitute spaced leg forming strips and a cover engaging strip, said leg 20 strip having a notched free end and being shiftable rearwardly with the said leg forming strips when the latter are folded, the top or cover having a slit to receive the notched free end of the said cover supporting strip, said leg forming strips having a cross piece 25 at their free ends and said box having angular tongues at opposite sides of the leg forming strips with which the cross strip is engageable to lock the leg forming strips in their folded effective positions.
5. A display box having a cover or lid adapted to be held in upright position to 50 expose the interior of the box, and also having a body whose bottom portion includes a member provided with integral foldable means forming supporting legs adjacent to the rear of the box in the folded position, and a 55 member carried by said foldable means and engageable with the cover or top to hold the latter in upright position when the leg forming means are folded.

PATRICK HENRY CASEY.
